UNITED STATES PATENT OFFICE.

NORMAN T. HARRINGTON, OF DETROIT, MICHIGAN, ASSIGNOR TO OLDS MOTOR WORKS, OF DETROIT, MICHIGAN, A CORPORATION.

RETAINER FOR ANTIFRICTION-BEARINGS.

No. 838,111.

Specification of Letters Patent.

Patented Dec. 11, 1906.

Application filed May 13, 1905. Serial No. 260,246.

To all whom it may concern:

Be it known that I, NORMAN T. HARRINGTON, a citizen of the United States, residing at Detroit, in the county of Wayne and State of Michigan, have invented certain new and useful Improvements in Retainers for Antifriction-Bearings, of which the following is a specification, reference being had therein to the accompanying drawings.

10 The invention relates particularly to ball retainers especially designed for use in connection with wheels of automobiles; and it consists in the novel construction of retainer and the peculiar arrangement and combination of its parts, as will be herein-after described.

15 In the drawings illustrating my invention, Figure 1 is a vertical central section through the retainer. Figs. 2 and 3 are detached perspective views, showing the manner of applying the yielding retaining device to the retainer proper; and Fig. 4 is a perspective view of the retaining means.

20 Heretofore in the construction of retainers for the purpose specified it has been the practice to form at the inner edge of the retainer a rigid flange to prevent the balls from dropping from the retainer on the application of the latter to the wheel or other place where it is to be used. This has been found 25 exceedingly objectionable, for the reason that in applying the wheel to the axle portions of the rigid inner flange are in many instances chipped or broken off and falling within the ball-race interfere materially with the proper 30 operation of the bearing.

35 The present invention is adapted to overcome these difficulties; and it consists, primarily, in providing a ball-retaining device 40 about the inner edge of the retainer proper of yielding material—that is, of some material relatively softer than that of which the retainer proper is made—and, further, in making the retaining means detachable, so that 45 when bent or otherwise injured it may, if desired, be withdrawn for the purpose of repair or renewal.

Referring to the drawings, the retainer

50 consists of a ring-shaped base section A, having an inclosing wall or flange B at its outer edge, preferably formed by turning up said edge in the manner indicated in Fig. 1. In proximity to the top of said flange or wall I form an annular groove C, in which the retaining-plate D is inserted in the usual manner.

55 The retaining means at the inner edge of the base, (indicated by the reference-letter a,) is preferably in the form of a thimble E, of softer material than the retainer proper, 60 which extends above the base-section A a sufficient distance to perform its function of holding the balls in place, and is itself held to the retainer by overturning its lower edge b in a manner to engage the bottom or lower 65 face of the base-section. Preferably the thimble is formed with a lateral annular flange c intermediate its edges, which when the retaining device is in place rests upon the section A, and, as previously stated, the 70 thimble is held from movement by turning over its lower edge, as may be easily effected by reason of the soft material of which the thimble is composed.

75 It will be obvious from the construction of the retainer that the retaining means described may be readily inserted and withdrawn when desired and that the danger of breakage is reduced to a minimum, as the securing flange will yield when accidentally 80 brought in contact with the axle-spindle upon the application of the wheel to the vehicle.

What I claim as my invention is—

85 A retainer for antifriction-bearings, comprising a ring-shaped base-section, an inclosing wall at the outer edge thereof, and a thimble of yielding material fitted within the section-opening and having annular flanges 90 engaging the opposite sides of the base.

95 In testimony whereof I affix my signature in presence of two witnesses.

NORMAN T. HARRINGTON.
